DESIGN FOR A BRASSIÈRE OR SIMILAR ARTICLE

George A. Kaufmann, Essex Fells, N. J.

Application July 21, 1936, Serial No. 63,967

Term of patent 7 years

To all whom it may concern:

Be it known that I, George A. Kaufmann, a citizen of the United States, residing at Essex Fells, county of Essex, State of New Jersey, have invented a new, original, and ornamental Design for a Brassière or Similar Article, of which the following is a specification, reference being had to the accompanying drawing, forming a part thereof.

Fig. 1 is a perspective view of a brassière showing my new design;

Fig. 2 is a front perspective view of the same; and

Fig. 3 is a perspective view of the same from the back.

I claim:

The ornamental design for a brassière or similar article, as shown.

GEO. A. KAUFMANN.
